CLAIM

The ornamental design for a laptop stand, as shown and described.

DESCRIPTION

FIG. 1 is a front, top, left isometric view of the laptop stand; FIG. 2 is a front, bottom, right isometric view of the laptop stand;

FIG. 3 is a top view of the laptop stand, and the bottom view of the laptop stand is a mirror image of the top view;

FIG. 4 is a left view of the laptop stand, and the right view of the laptop stand is a mirror image of the left view;

FIG. 5 is a front view of the laptop stand;

FIG. 6 is a back view of the laptop stand;

FIG. 7 is a front, top, left isometric view of the laptop stand supporting a laptop computer in a first configuration; and,

FIG. 8 is a front, bottom, left isometric view of the laptop stand supporting a laptop computer in a second configuration.

The broken line showing of a laptop in FIGS. 7-8 is included for the purpose of illustrating the laptop stand in use and forms no part of the claimed design.
